UNITED STATES PATENT OFFICE

112,218

DESIGN FOR A FLOOR LAMP

Hilyard R. Robinson, Washington, D. C., and Aksel J. C. Knudstrup, Vienna, Va.

Application August 3, 1938, Serial No. 79,072

Term of patent 7 years

To all whom it may concern:

Be it known that we, Hilyard R. Robinson and Aksel J. C. Knudstrup, citizens of the United States, residing at Washington, District of Columbia, and Vienna, county of Fairfax and State of Virginia, have invented a new, original, and ornamental Design for a Floor Lamp, of which the following is a specification, reference being had to the accompanying drawing, forming a part thereof.

In the drawing:

We claim:

The ornamental design for a floor lamp, as shown.

HILYARD R. ROBINSON.
AKSEL J. C. KNUDSTRUP.
